Application December 5, 1950, Serial No. 199,172

7 Claims. (Cl. 250—36)

The present invention relates to pulse generators and more particularly to a pulse generator capable of emitting a specified number of pulses upon being energized.

It is an object of the invention to provide a simple glow tube pulse generator emitting a specified number of output pulses whenever the circuit is energized.

Briefly, the present invention includes a glow discharge tube having an anode and a plurality of cathodes therein immersed in an ionizable gas at glow discharge pressure. A source of positive potential is connected to the anode through a limiting resistor, and a time constant circuit is connected to each cathode, and to the negative end of the source. Each time constant circuit is designed to have a different time constant.

A switch is provided in the source circuit which, when closed, will cause the tube to strike. Because of the different RC combinations, the cathode connected to the circuit having the shortest time constant will strike first, followed by the striking of additional cathodes in order of the time constants of their connected circuits. By means of an output circuit connected to the anode, the voltage drops across the limiting resistor, as each of the cathodes strike, are differentiated as output pulses. Thus, a train of pulses is generated equal in number to the number of cathodes, and spaced in time according to the time constants of the connected circuits.

The invention will be more fully understood by reference to the figure which shows one preferred circuit embodying the present invention.

In the figure, an envelope 1 containing an ionizable gas at glow discharge pressure, such as for example, helium at 200 mm. mercury pressure, also contains an anode 2 and a plurality (five in this instance), of cathodes 3, 4, 5, 6 and 7. The cathodes 3, 4, 5, 6 and 7 are respectively connected to one end of cathode resistances 3r, 4r, 5r, 6r and 7r, the other ends of which are connected together and to the negative end of a potential source 10 through a switch 8. The positive end of source 10 is connected to anode 2 through an anode line 11 connected to anode 2 through an anode resistance 12.

Cathodes 3, 4, 5, 6 and 7 are connected to anode line 11 through cathode capacities 3c, 4c, 5c, 6c and 7c respectively, thereby forming a time constant circuit connected to each cathode. The values of the resistances and the capacities are chosen such that the time constant is progressively larger for each cathode. A suitable series of time intervals, given only by way of an example, is as follows:

Cathodes 3 RC=1 time unit
 Cathode 4 RC=2 time units
 Cathode 5 RC=4 time units
 Cathode 6 RC=8 time units
 Cathode 7 RC=16 time units

An output line 15 containing an output condenser 16 is connected to anode 2.

In operation, switch 8 is closed, and current from source 10 will charge capacity 3c sufficiently that a glow dis-

charge will be struck between cathode 3 and anode 2 before any other of the capacities 4c, 5c, 6c and 7c are charged sufficiently to cause a glow to be struck on their connected cathodes. However, as time passes, each of the other capacities will in turn be charged and a glow will be established between the particular cathode and anode 2, until all of the cathodes have had the glow discharge struck thereon.

As each glow discharge is struck, a drop in voltage at the anode 2 will be realized due to additional current flowing through anode resistor 12. The resistor 12 and output line capacity 16 combination differentiates these voltage drops, causing a pulse on the output side of capacity 16 as each cathode is struck. The number of pulses appearing in the output will, therefore, be equal to the number of cathodes in the tube, and the pulse spacing will be in accordance with the relative time constants of the cathode connected circuits. Thus, while I have shown and described a tube having only five cathodes, any number desired can be used, with any desired time spacing of the output pulses. It is also to be noted that switch 8 can be any type of switch, such as for example, an electronic gate.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise a preferred form of putting the invention into effect, and the invention is, therefore, claimed in any of its forms or modifications within the legitimate and valid scope of the appended claims.

What is claimed is:

1. A pulse generator comprising a tube having an envelope containing an anode and a plurality of cold cathodes immersed in an ionizable gas at glow discharge pressure, a separate and different time constant circuit connectable between each of said cathodes and said anode through a potential source sufficient to strike all of said cathodes, means for connecting all of said time constant circuits simultaneously to said source to strike said cathodes in the order of the time constants of the circuits connected thereto, and means for differentiating resultant changes in current flow to said anode as output pulses.

2. A pulse generator in accordance with claim 1 where-in said time constant circuits are arranged to have time constants causing said cathodes to strike in a related series of time intervals.

3. A pulse generator comprising a tube having an envelope containing an anode and a plurality of cold cathodes immersed in an ionizable gas at glow discharge pressure, a separate and different time constant circuit connectable between each of said cathodes and said anode through a potential source sufficient to strike all of said cathodes and through a series anode resistor, an output circuit including a capacity connected to said anode, and means for connecting all of said time constant circuits simultaneously to said source to strike said cathodes in the order of the time constants of the circuits connected thereto.

4. In a pulse generator for producing a specified number of electrical pulses upon being energized, a tube having an envelope containing an anode and a plurality of cold cathodes immersed in an ionizable gas at glow dis-

charge pressure, a single load resistance connected at one end to said anode, a source of potential connected at one end to the other end of said load resistance, a plurality of cathode resistances, one thereof connected to each of said cathodes, a plurality of capacities, one thereof being connected between each of said cathodes and said other end of said load resistance, and means for simultaneously connecting all of said cathode resistances to said anode through said source and said load resistance in series, thereby creating a time constant circuit connected between each cathode and said anode, the resistance capacity combination of each cathode connected circuit being different to provide different time constants thereof, whereby said cathodes are struck in the order of the time constants of the connected circuits, and whereby the incremental changes in voltage across said load resistance as said cathodes are struck provide a basis for output indications in accordance with the time of striking.

5. A pulse generator comprising a tube having an envelope containing an anode and a plurality of cold cathodes immersed in an ionizable gas at glow discharge pressure, a source of potential connected at one end to said anode, a plurality of resistances, one thereof connected to each of said cathodes, a plurality of capacities, one thereof being connected between each of said cathodes and said anode, and means for simultaneously connecting all of said resistances to said anode through said source, thereby creating a time constant circuit connected between each cathode and said anode, the resistance-capacity combination of each cathode connected circuit being different to provide different time constants thereof, whereby said cathodes are struck in the order of the time constants of the connected circuits and means for differentiating resultant changes in anode current as output pulses.

35 6. A pulse generator comprising a tube having an envelope containing an anode and a plurality of cold cathodes immersed in an ionizable gas at glow discharge pressure, a source of potential connected at one end to said anode, a plurality of resistances, one thereof connected to each of said cathodes, a plurality of capacities, one thereof being connected between each of said cathodes and said anode, means for simultaneously connect-

10 ing all of said resistances to said anode through said source, thereby creating a time constant circuit connected between each cathode and said anode, the resistance-capacity combination of each cathode connected circuit being different to provide different time constants thereof, whereby said cathodes are struck in the order of the time constants of the connected circuits, an anode resistance in series with said anode and said time constant circuits, and a capacitative output line connected to said anode.

15 7. A pulse generator for producing a specified number of electrical pulses, comprising a glow-discharge tube having an envelope containing a single anode and a plurality of cathodes all in operating relationship with said anode and immersed in an ionizable gas at glow discharge pressure, a limiting resistance connected at one end to said anode, a source of direct current potential connected at one end to the other end of said limiting resistance, a plurality of separate additional resistances, one thereof connected to each of said cathodes, a plurality of capacitances, one thereof connected between each of said cathodes and said other end of said limiting resistance, means for simultaneously connecting all of said additional resistances to the other end of said direct current potential source, thereby creating a time constant circuit connected between each cathode and said anode, the resistance-capacity combination of each said time constant circuit being different to provide different time constants thereof, and means for differentiating resultant abrupt changes in voltage across said limiting resistance into output pulses, as striking of each cathode occurs, whereby the number and spacing of said output pulses after said connecting means closes said circuits is governed by the number and value of said time constant circuits.
